UNITED STATES PATENT OFFICE

2,389,328

APPARATUS FOR TREATING PETROLEUM

David W. Stilwell, Los Angeles, Calif.

Application May 18, 1942, Serial No. 443,409

4 Claims. (Cl. 196—5)

My invention relates to the treatment of oil, primarily crude petroleum, the principal object being the removal of water, sand, emulsion, and foreign matter generally.

This has previously been accomplished in several ways, as for example (a) breaking down the viscosity by heat or solvent, and (b) use of chemicals. Prior methods involve various disadvantages well known in the art. The purpose of breaking down the viscosity is to allow foreign matter, which is heavier than oil, to drop, and the washed oil to flow over into tanks or elsewhere for further handling.

The prior methods under example (a) which utilize heat, employ hot water or steam for heating the body of crude to be washed. If the temperature of the water exceeds 212° F., a back pressure of 60 to 100 lbs. must be maintained to keep the water liquid. The use of steam involves higher pressures. Any water or steam system is subject to pressure, requiring a circulating system of sufficient strength to withstand high pressures, and generally complicating the system, requiring constant and skillful attention during operation. The system is also subject to oxidation and other deteriorating effects, and subject to the danger of a split line, broken fittings, and blow up, and the danger of burning or otherwise injuring workmen.

An object of my invention is to provide a method of washing oil in which the heating element is a highly refined lubricating oil. Among other advantages, this has the following:

1. There is only atmospheric pressure on the system.
2. The heat transfer of oil is about twice as efficient as water or steam, thus reducing fuel consumption.
3. There is no oxidation or other deteriorating effects on the apparatus.
4. The system may be virtually automatic, requiring a minimum of attention.

Another object is the provision of a novel form of wash tank in which increased efficiency is realized.

These, and other objects of my invention, will be made more apparent upon consideration of the description and claims.

In the drawings:

Figure 1 is a diagrammatic plan view of an apparatus suitable for carrying out my improved method.

Figure 2 is a diagrammatic elevational view of the same.

Figure 3 is a vertical cross section of my novel wash tank indicated in Figures 1 and 2.

Figure 4 is a fragmentary bottom view of the separator plates and distributing heads in the wash tank, as seen on the line 4—4 of Figure 3.

Referring to Figures 1 and 2, an apparatus suitable for performing my method may comprise a gas line 10, a scrubber 11, a gas regulator 12, a solenoid gas valve 13, a thermostat 14, and a gas heater 15, for heating the lubricating oil which is carried in the oil line 16.

The heater includes a burner 17, and coils 18 in staggered relation as illustrated, or any other desired arrangement. These coils form an element in the oil line 16, which, as will become apparent, is a re-circulating system.

At suitable locations in the oil line 16 are a pump 19 and a surge tank 20. I may also provide an overflow tank 21, and thermometers 22 and 23 in the hot oil and return sections respectively, and a pressure gage 24.

The oil line includes one or more coils (later described) in a wash tank 26. In contemplating my method, any form of coils and wash tank 25 may be employed, it being essential only that the coils be located in a suitable tank within the region occupied by a body of petroleum to be treated, the tank affording a receiving chamber for the petroleum to be treated, a space or settling chamber wherein water, sand, emulsion and other foreign matter may gravitate, and a temporary storage chamber with preferably a discharge overflow for taking off treated oil. Such features, and additional details are shown in

Figures 3 and 4, and will be more fully described in connection with my novel form of wash tank.

In practicing my method, a highly refined lubricating oil is heated to the desired temperature (ordinarily about 250° to 275° F.) in the heater 15, and delivered through the oil line 16 in the direction of arrow 27 (Figure 2) to the coils in the wash tank, circulated therethrough, and returned to the surge tank 20. A heat exchange takes place within the wash tank, the lubricating oil giving up its heat through the coils to the body of crude within the tank, breaking down the viscosity of the crude, and allowing foreign matter to settle out. The lubricating oil returned to the surge tank will ordinarily have a temperature of 150° to 160° F.; although the temperatures of the lubricating oil introduced into the wash tank, and its temperature after the heat exchange, may vary within wide limits to meet operating conditions. From the surge tank, the

50
55

lubricating oil is drawn by the pump 19, and pumped through the coils 18 in the heater for re-heating and recirculation.

There is no requirement for any pressure on the oil line 16, because oil of the character employed may be heated at atmospheric pressure to any temperature necessary in a system of the character described without vaporizing. It is possible with my method, to eliminate the pump, but in the interest of efficiency a forced circulation is preferred.

In a sense the oil line 16 is a closed circulating system, but I intend to convey the thought of continuous recirculation, not in the presence of any elements which might create a back pressure.

My oil line may be open to the atmosphere, as illustrated in the surge tank 20 and overflow tank 21. The surge tank is provided with a fill spout 29, and a vent 30. The vent is to take off vapors, and eliminate any tendency to back pressure in the line, or vapor locks. An overflow line 31 carries off excess oil from the surge tank into the overflow tank, so that waste of oil is avoided.

The oil used as the heating medium must be specially prepared. It must be a highly refined lubricating oil from which foreign matters have been removed, and must be treated with a mechanical wash, as for example, forcing it through filters. An acid equalizer can be used in place of a mechanical wash, but if conditions are not exactly right, the resulting oil will sludge up under use. For consistently good results, the mechanical wash should be used.

Lubricating oil, so prepared, furnishes a heating medium which is efficient, and can be recirculated indefinitely without its desirable characteristics changing. It absorbs heat faster than water and gets rid of it quicker, being about twice as efficient as water or steam, and therefore more economical on fuel.

So far as I am aware, I am the first to use oil as a heat transfer agent for reducing the viscosity of crude in a washing or treating operation.

By my method, the body of crude in the washing tank may be maintained at the desired temperature, notwithstanding a continuous flow of crude through the wash tank.

It will be apparent that the particular apparatus described is illustrative only, and that modifications may be utilized without departing from the basic conception of my method. The essence of my method invention resides in circulating a highly refined heated lubricating oil through a conductor in a body of crude to break down the viscosity of the crude and allow foreign matter to gravitate therefrom.

Referring to Figures 3 and 4, my novel washing tank 26 comprises a shell 40 suitably mounted on a concrete or other base 41. Also mounted on the base 41 is a frame 42 which supports a cone 43 forming a settling chamber. A shelf 44 abutting the upper edge of the cone, rests upon the shell 40, and a temporary storage tank wall 45 rises from the shelf 44. A drum 46 provided with screens 47 rests upon the upper edge of the cone, and is formed with a cover 48. A plurality of vertical angle iron supports 49, welded at the bottom to brackets 50, and at the top to brackets 51, are thus located adjacent the outer surface of the drum 46, and support the convolutions of pipe forming a coil 52 surrounding the drum.

A crude oil inlet 53 empties into a central receiving chamber 54, the cylindrical walls forming the latter being carried on diagonal braces 55

which have their footing on the inside of the cone 43.

Concentric spreader cones 56 and 57 formed with slots 58 depend from the walls of the chamber 54.

The lower end of the chamber 54 is divided by radially arranged separator plates 59, from which extend distributing heads 59. Each head 59 comprises a V bottom 60 having its greatest relative depth at the junction of the separator plates, vertical sides 61 of increasing relative height toward the outer end, a top 62 extending from the wall of chamber 54, and an outer end closure 63 covering the upper half of the end opening. The sides and end closure are formed with slots 64.

A second coil 65 is located within the chamber 54. This coil is a vertical type, and is a part of the oil line 16 which includes coil 52.

A tank outlet 66 provides for overflow of treated petroleum to storage or shipping tanks.

In operation, crude oil to be washed passes in through the inlet 53. Ordinarily the crude will have been passed through a gas separator (not shown), so that in the wash tank substantially gas free petroleum is to be treated for the removal of water, sand and other impurities.

A heating medium such as the highly refined lubricating oil previously described, heated to the desired temperature, is passed through the oil line 16, including coils 52 and 65.

The incoming crude oil is initially heated in the chamber 54, by the exchange of heat from the coil 65. The viscosity is broken down. Any gas freed will rise and be disposed of by any conventional means desired. The heated crude oil will be distributed by the separator plates 59 and distributing heads 59 into the cone 43. The heavier foreign elements will tend to pass with the oil through the end openings, and the remainder of the oil will pass in ribbon form through the slots 64 in the sides 61 and ends 63. The foreign matter will accumulate by gravity in the lower part of the cone, and may be continuously or periodically drawn off through a pipe 67 and valve 68, assisted if desired, by a pressure fluid jet 69.

The crude oil rises into the drum 46, the bulk of it first encountering the spreader cones 56 and 57 passing through the slots 58. It enters the drum, and passes through the screens 47 for the further removal of any foreign matter, and into the tank or temporary storage chamber 45, the petroleum in which is maintained hot by the coil 52, to aid in maintaining the chamber 54 heated, and to assist the flow of treated petroleum through the outlet 66 to storage or shipping facilities.

Having described my invention, what I claim as new and desire to secure by Letters Patent is:

1. A petroleum wash tank comprising: a receiving chamber, vertical heating coils therein, distributing heads extending outwardly from said chamber, spreader cones extending from said chamber and overlying the distributing heads, a cone below the chamber to receive foreign matter passing downward through petroleum in the chamber, and a passage permitting the flow of petroleum out of said cone.

2. A petroleum wash tank comprising: a receiving chamber, vertical heating coils therein, distributing heads extending outwardly from said chamber, spreader cones extending from said chamber and overlying the distributing heads, a drum embracing the lower end of the receiving chamber and the upper end of the cone, a cone

below the chamber to receive foreign matter passing downward through petroleum in the chamber, and a passage permitting the flow of petroleum out of said cone.

3. A petroleum wash tank comprising: a receiving chamber, vertical heating coils therein, distributing heads extending outwardly from said chamber, spreader cones extending from said chamber and overlying the distributing heads, a drum embracing the lower end of the receiving chamber and the upper end of the cone, heating coils around the drum, a cone below the chamber to receive foreign matter passing downward through petroleum in the chamber, and a passage permitting the flow of petroleum out of said cone. 15

4. A petroleum wash tank comprising: a receiving chamber, vertical heating coils therein, distributing heads extending outwardly from said chamber, spreader cones extending from said chamber and overlying the distributing heads, a drum embracing the lower end of the receiving chamber and the upper end of the cone, heating coils around the drum, a cone below the chamber to receive foreign matter passing downward through petroleum in the chamber, and a passage permitting the flow of petroleum out of said cone. 10
